**PROCESS FOR ISOMERIZATION OF 1-OLEFINS
AND USE OF ISOMERIZED PRODUCT IN
ALKYLATION**

Donald H. Belden, North Riverside, Ill., assignor to Universal Oil Products Company, Chicago, Ill., a corporation of Delaware

Application September 29, 1952, Serial No. 312,123

7 Claims. (Cl. 260—683.4)

This invention relates to a process for alkylating hydrocarbons and as an integral, preliminary step of the process, to the method of converting the terminally bonded isomer component of an olefinic alkylating agent containing the same to olefins having a more centrally located double bond. More specifically, the invention concerns a method for converting a 1-olefin into a 2-olefin or other more centrally bonded olefin position isomer by means of a combination process involving hydrofluorination of a 1-olefin containing hydrocarbon fraction, subjecting the resulting product to dehydrofluorination and thereafter repeating the hydrofluorination-dehydrofluorination cycle until substantially all of the original 1-olefin is converted to the double bond position isomer thereof.

One object of the invention is to provide a process for converting a mixture of olefinic hydrocarbon isomers into an olefinic hydrocarbon having a particular structure more desirable for the production of a motor fuel or aviation alkylate therefrom. Another object of the invention is to convert a 1-olefin to an isomer thereof in which the double bond occupies a more centrally located position in the carbon atom chain of the olefin molecule. Still another object of the invention is to provide a process for the manufacture of a more highly branched chain hydrocarbon alkylate having substantially greater antiknock value than the corresponding alkylate product obtainable from the olefinic hydrocarbon alkylating agent which is not subject to the pretreatment comprising the method of the present process.

In one of its embodiments the present invention concerns a process for condensing an alkylatable hydrocarbon with a mono-olefinic hydrocarbon containing at least 4 carbon atoms per molecule which comprises subjecting an olefinic hydrocarbon having a terminal double bond to at least one isomerizing reaction cycle wherein the terminal double bond of said olefinic hydrocarbon is shifted to an intermediate position in the carbon atom chain, said isomerizing reaction comprising subjecting said terminally bonded olefinic hydrocarbon to hydrofluorination in the presence of not more than the quantity of hydrogen fluoride which will completely dissolve in said olefinic hydrocarbon, thereafter subjecting the resulting alkyl fluoride to dehydrofluorination and reacting the resulting product with said alkylatable hydrocarbon.

Another embodiment of the invention relates to the process for effecting substantially complete isomerization of a terminally bonded olefinic hydrocarbon containing at least 4 carbon atoms per molecule to an isomer thereof having a double bond more centrally located in the carbon atom chain of said olefin, which comprises subjecting said terminally bonded olefinic hydrocarbon to hydrofluorination in the presence of not more than the quantity of hydrogen fluoride which will completely dissolve in said olefinic hydrocarbon and thereafter subjecting the resulting product to dehydrofluorination.

It is commonly recognized that branched-chain hydro-

carbons of the paraffin series have less tendency to knock upon combustion under compression in a spark-fired internal combustion engine than the corresponding straight-chain isomers. It is also known that a more highly branched-chain aliphatic hydrocarbon is obtained in the alkylation of isoparaffins with olefinic hydrocarbon alkylating agents in which the double bond of the olefin occupies a position in the carbon atom chain other than on the terminal carbon atom. That is, a 2-olefin hydrocarbon yields a more branched chain alkylate than a 1-olefin and the same is generally true for the 3-olefins, 4-olefins, etc., the carbon atom containing the least hydrogen generally being involved in the alkylation reaction as the point of attachment to the isoparaffin alkyl acceptor. The same general principles are believed to obtain in the alkylation of aromatic hydrocarbons containing a replaceable nuclear hydrogen atom, an isoalkyl aromatic hydrocarbon alkylate being the product formed as a result of the alkylation reaction. For these reasons, it is preferred that the olefinic hydrocarbon supplied to the alkylation reaction as the source of the alkyl group in the production of motor fuel or aviation alkylates or in the manufacture of isoalkyl aromatic hydrocarbons be an olefinic hydrocarbon in which the double bond occupies a more centrally located position in the carbon atom chain of the olefin molecule; that is, the preferred olefinic hydrocarbons for use as alkylating agents are monoolefins other than the 1-olefin isomers in which the double bond occupies a terminal carbon atom of the molecule.

Thus, butene-2 is preferred over butene-1 as alkylating agent for condensation with isobutane, isopentane, or other iso-paraffinic hydrocarbons. Similarly, pentene-2, pentene-3, hexene-2, hexene-3, 2-methyl-hexene-3, 2,3-dimethyl-pentene-2, octene-2, octene-3, octene-4, etc. are preferred over the corresponding straight chain or branched chain pentene-1, hexene-1, octene-1, and higher 1-olefin homologs for alkylation purposes. By means of the process of the present invention, a method of isomerizing 1-olefins to their olefin isomers containing a corresponding number of carbon atoms is provided whereby the more desirable intermediate position isomers may be obtained for alkylation purposes from any of the above 1-isomers or mixtures thereof or hydrocarbon mixtures containing a substantial proportion of the 1-isomer.

The isomerization process provided herein involves a method of subjecting a 1-olefinic hydrocarbon or a mixture of hydrocarbons containing a 1-olefin to hydrofluorination whereby the corresponding allyl fluoride is formed and thereafter dehydrofluorinating the alkyl fluoride product. The hydrofluorination reaction is effected in the presence of sufficient hydrogen fluoride to react at least partially with the 1-olefins present in the mixture, and preferably in the presence of not more than an amount of hydrogen fluoride which will completely dissolve in the hydrocarbon feed stock to the process, since in the presence of a free hydrogen fluoride phase, the olefinic components of the feed stock tend to undergo undesirable polymerization and hydrogen transfer reactions, rather than forming the desired alkyl fluoride therefrom. In the hydrofluorination reaction the 1-isomer is believed to undergo conversion to a secondary alkyl fluoride which upon dehydrofluorination is converted into a position isomer of the original 1-olefin which contains the double bond in an intermediate position in the olefin chain. It is also believed that the conversion of the 1-olefin to the more centrally located double bond position isomer through intermediate secondary alkyl fluoride formation continues in the indicated direction until the 1-olefin is converted to the position isomer substantially to extinction of the 1-olefin. Furthermore, it is believed that during the alternate hydrofluorination-dehydrofluorination reaction cycle, the intermediate alkyl fluoride does

not dehydrofluorinate to any substantial degree to the initial 1-olefin contained in the feed stock; therefore, the formation of the alkyl fluoride as an intermediate product of the reaction insures the ultimate complete conversion of the 1-olefins contained in the feed stock to the isomer having a centrally located double bond position.

Suitable olefinic hydrocarbon mixtures containing the 1-olefin isomer may be obtained from any convenient source, but the olefinic hydrocarbons formed by dehydrating normal primary, aliphatic alcohols are almost exclusively the 1-olefin isomer and, therefore, are particularly adapted for use as feed stock in the present conversion process. Other sources of 1-olefins include the normally gaseous and normally liquid fractions of the hydrocarbon product formed by thermally or catalytically cracking a liquid hydrocarbon feed stock, the olefinic products generally comprising a mixture of the various olefinic isomers, including 1-olefins. Olefinic hydrocarbons containing the 1-isomer are also the end product of the dehydrohalogenation of alkyl halides, as for example, the dehydrochlorination product of an alkyl chloride such as butyl chloride, amyl chloride, octyl chloride etc.

The isomerization reaction involved in the present process is generally applicable to individual olefinic hydrocarbons or mixtures thereof, the components of which contain at least 4, up to about 12, carbon atoms per molecule, that is, from butene-1 to dodecene-1. In the manufacture of motor fuel and/or aviation alkylates for which the present process is a particularly useful improvement, a low molecular weight isoparaffinic hydrocarbon, such as isobutane, isopentane, one of the isohexanes or isoheptane is condensed in the presence of an alkylation catalyst with a butylene, amylene, and/or hexene. A fraction comprising predominantly low molecular weight olefins is separated from an olefinic feed stock and subjected to the present isomerization treatment in a preliminary conversion reaction prior to the alkylation step.

It is to be emphasized that although the present isomerization method is particularly adapted to the conversion of mixtures of olefinic hydrocarbon isomers in which the 1-olefin isomer is predominant, the reaction may be applied with similarly advantageous results to olefinic mixtures in which the 1-isomer constitutes merely a minor proportion of the total olefin content of the mixture, the conversion of the isoalkyl fluoride to a different position isomer being the principal reaction involved in the process. A particularly preferred feed stock is a mixture containing butene-1 and isobutylene which upon alkylation with isobutane is converted to the highly desirable motor fuel and aviation alkylate: iso-octane (that is, 2,2,4-trimethylpentane) which has high antiknock properties when used as fuel in internal combustion engines.

Suitable feed stocks which may be alkylated with the present isomerized olefins include isoparaffinic hydrocarbons as well as aromatic hydrocarbons containing a nucleophilic substitutable hydrogen atom. Thus, isoparaffins such as isobutane, the isopentane paraffins, such as 2,2-dimethylpropane, 2-methylbutane, the isohexane paraffins such as 2,3-dimethylbutane, 2,2-dimethylbutane and 2-methylpentane and homologs thereof, generally containing not more than about 12 carbon atoms per molecule may be alkylated by means of the present process. Of the aromatic hydrocarbons which may be alkylated with the present isomerized olefins to form isoalkylaromatic alkylates, including phenyl as well as polycyclic aromatic hydrocarbons, generally the alkylbenzene derivatives are preferred because of the substantially greater yields of alkylate obtained therefrom. Suitable aromatic hydrocarbon feed stocks to the present alkylation process include benzene, toluene, a xylene or a mixture of xylene isomers, a trimethylbenzene or other mono-, di-, and tri-alkyl substituted benzenes; naphthalene, the mono- and polyalkyl-substituted naphthalenes, phenanthrene, etc. the

aromatic hydrocarbon feed stock to the present process being characterized in that the aromatic nucleus contains a replaceable hydrogen atom.

The isomerization reaction of the present process is obtained by contacting the olefin feed stock containing the 1-olefin isomer with hydrogen fluoride or hydrofluoric acid at isomerizing conditions, the quantity of hydrogen fluoride in the reaction being controlled and specifically limited to an amount less than that required to form a separate phase distinct from the hydrocarbon phase, that is, less than the amount soluble in the hydrocarbon feed stock. It has been observed that by limiting the amount of hydrogen fluoride charged with the butene-1 containing olefin fraction into the isomerization reactor to an amount not more than the quantity which will dissolve completely in the olefinic feed, the reaction occurring in the isomerization reactor may be controlled so as to effect alternate hydrofluorination and dehydrofluorination of the butene-1 feed without attending alkyl and hydrogen transfer, polymerization and other side reactions foreign to the present process, which reactions would otherwise occur in the presence of a greater quantity of hydrogen fluoride to reduce the yield of isomerized olefin monomer. In the presence of only sufficient hydrogen fluoride to completely dissolve in the olefinic feed stock charged to the process, on the other hand, conversion of the 1-olefins to secondary alkyl fluorides occurs substantially to the exclusion of the aforementioned side reactions and the objects of the present invention are realized. The olefinic feed is desirably mixed with a diluent, preferably a paraffinic hydrocarbon which is inert to the action of the hydrogen fluoride and dehydrofluorination catalyst prior to subjecting the 1-olefin containing feed stock to isomerization. Thus, a butene-1 containing hydrocarbon feed may be diluted with iso-butane prior to the isomerization reaction, preferably in an amount equivalent to from about 0.5 to about 10 volumes of butane per volume of butene-1 in the olefin-containing fraction utilized as feed stocks.

In accordance with the present process, isomerization of the 1-olefin containing feed stock to an olefinic hydrocarbon having a more centrally located double bond is accomplished by subjecting a mixture of the olefinic feed and hydrogen fluoride (dissolved in the inert paraffinic hydrocarbon diluent and containing less hydrogen fluoride than required to form a separate phase) to hydrofluorination, thereby forming secondary alkyl fluorides of the 1-olefins contained in the mixed olefinic feed and thereafter passing the stream of hydrogen fluoride, inert hydrocarbon, and/or olefins and alkyl fluorides into a reactor containing a dehydrofluorination catalyst wherein the alkyl fluorides undergo substantial conversion to hydrogen fluoride and an olefin in which the double bond is more centrally located in the carbon atom chain of the olefin molecule. The hydrofluorination and successive dehydrofluorination reactions may be alternately repeated in a number of successive cycles until the 1-olefin components are substantially completely converted to their isomers having more centrally located double bonds, that is, until substantial extinction of the 1-olefin components of the mixed feed. Hydrofluorination of the olefinic feed may be obtained by mere contact between the olefinic feed and the hydrogen fluoride, preferably in liquid phase, at temperatures of from about 0° to about 150° C. Since, however, the subsequent dehydrofluorination stage must generally be operated at a somewhat higher temperature level, the hydrofluorination reactor is preferably maintained at substantially the same temperature as the dehydrofluorination zone, thereby eliminating the necessity for alternate cooling and heating between the hydrofluorination and dehydrofluorination stages in a multiple cycle operation. Since hydrofluorination is more readily obtained by increasing the intermolecular contact between the hydrogen fluoride and olefinic feed stock, it is generally preferred to mix the

reactants by any suitable form of mixing device or means. Accordingly, the hydrofluorination zone is preferably packed with a hydrogen fluoride resistant solid contact material in particle form, such as copper pellets, saddles or other distributed particles placed therein in such manner as to allow free flow of the mixture of hydrogen fluoride and olefinic feed through the bed of contact material.

Dehydrofluorination of the alkyl fluorides formed in the preceding hydrofluorination zone is preferably effected in the presence of a catalytic agent which enhances the rate of dehydrofluorination and the yield of isomerized olefin from the alkyl fluorides. Typical of such catalytic agents are solid inorganic materials such as aluminum fluoride, calcium fluoride, potassium fluoride, certain metals such as copper, nickel, chromium etc. and other metals and inorganic fluoride salts which are stable and retain their identity at the operating conditions maintained in the dehydrofluorination zone. In the presence of such dehydrofluorinating agents, the secondary alkyl fluorides formed in the preceding hydrofluorination zone undergo dehydrofluorination at temperatures of from about 30° to about 300° C., preferably at temperatures of from about 40° to about 150° C. The pressures at which the hydrofluorination and dehydrofluorination reactions occur within the isomerization reactor are such as to maintain the feed and hydrogen fluoride reagent in substantially liquid state, preferably at pressures of from atmospheric to about 500 lbs./in.², depending upon the temperature maintained in the respective zones.

The isomerized 1-olefin removed from the isomerization reactor in the form of the olefin or as an alkyl fluoride is thereafter mixed with a paraffinic fraction containing as isoparaffin, that is, a branched chain paraffin hydrocarbon, or with an alkylatable aromatic hydrocarbon containing a nuclearly substitutable hydrogen atom and the resulting mixture subjected to alkylating conditions in the presence of liquid hydrogen fluoride or substantially anhydrous hydrofluoric acid containing less than about 10% by weight of water as the alkylation catalyst. Where the alkylatable hydrocarbon is an isoparaffin present in the stream of olefinic feed stock, as for example, when the process is utilized to produce aviation alkylate, the reactants are self-contained in the effluent stream of the isomerization zone, although additional isoparaffin is preferably added to the effluent to increase the isoparaffin to olefin mole ratio to the level desired for alkylation, as hereinafter described. The alkylation reaction is preferably effected in a stirred pressure autoclave wherein the reactants and hydrogen fluoride catalyst may be maintained in substantially liquid phase, generally at temperatures of from about -30° to about 100° C., and preferably at from about 0° to about 50° C., although higher or lower temperatures may also be utilized to obtain the desired condensation of the hydrocarbon reactants. In order to reduce side reactions such as polymerization, polyalkylation etc., the reactants are charged into the alkylation reactor in a molar proportion of aromatic or isoparaffinic hydrocarbon to total olefin of at least 1 to 1 up to about 30 to 1 and preferably from about 10 to 1 to about 20 to 1, particularly when utilizing an aromatic hydrocarbon containing no other nuclear substituents, the latter being subject to polyalkylation.

The present invention is further illustrated with respect to specific embodiments thereof in the accompanying diagram and the description which follows. The diagram is described with respect to the alkylation of an isoparaffinic hydrocarbon, which in the illustration shown is isobutane, with a C₄ olefin fraction as the olefinic feed stock. The diagram also illustrates a multiple cycle hydrofluorination-dehydrofluorination zone packed with a suitable contacting material in the hydrofluorination zone and a dehydrofluorination catalyst in the dehydrofluorination zone.

Referring to the accompanying drawing, a C₄ paraffinic

hydrocarbon fraction, such as a predominantly isobutane fraction is charged into the process flow from storage through line 1 in amounts controlled by valve 2, the added isobutane being supplied in an amount which in addition to the isobutane recycled in the process is sufficient to maintain the proper iso-paraffin to olefin ratio for the subsequent alkylation stage of the process. Since the only isobutane removed from the process is the isobutane reacted with the olefinic alkylating agent to form alkylate product, the amount of fresh isobutane charged into the process through line 1 is the isobutane equivalent to the alkylate removed as product. The remaining isobutane required to provide the desired isobutane to butylene ratio for alkylation purposes is made up by recycling isobutane within the process flow. The C₄ fraction in liquid phase is transferred by means of pump 3 and line 4 into hydrogen fluoride saturator 5 comprising a fixed tower containing hydrogen fluoride in liquid phase wherein the paraffinic hydrocarbon stream is saturated with dissolved hydrogen fluoride. Since the present process is essentially cyclic with respect to the hydrogen fluoride catalyst involved, the amount of the reagent required for this purpose may be continuously recycled from subsequent recovery stages of the process, as hereinafter described. The recycled hydrogen fluoride is charged into zone 5 through line 6 in amounts controlled by valve 7. The resulting stream of C₄ paraffins containing dissolved hydrogen fluoride is removed from saturator vessel 5 through line 8 and mixed in line 8 with a butene-1 containing C₄ fraction introduced into the flow through line 9 in amounts determined by valve 9a. The latter butene-1 containing fraction may be obtained from any suitable source, such as the light pressure overhead from a thermally cracked petroleum fraction. Valve 9a controls the amount of butene-1 and other olefins, if any, admitted into line 8, the amount being determined by the rate of alkylate formation in subsequent stages of the process. The C₄ hydrocarbon hydrogen fluoride mixture formed in line 8 is passed through a suitable heat exchange unit, such as heater 10 which raises the temperature of the stream to the level desired in the succeeding isomerization reactor, preferably to a temperature of from about 40° to about 150° C. The stream at the above temperature and pressure conditions is removed from heater 10 through line 11 and charged into the bottom of isomerization reactor 12 wherein the HF-hydrocarbon mixture is subjected to alternate hydrofluorination and dehydrofluorination reactions occurring therein.

The hydrogen fluoride dissolved in the C₄ paraffin stream admitted into the process flow through line 1 or admitted with the isobutane recycle stream, hereinafter described, is generally sufficient to supply the required amount of hydrogen fluoride for isomerization of the butene-1 component of the olefinic feed to butene-2; however, under some circumstances it may be preferable to eliminate the C₄ paraffin hydrocarbon stream introduced by such means and introduce undiluted hydrogen fluoride from a separately maintained source of hydrogen fluoride in the form of hydrofluoric acid or liquefied hydrogen fluoride, as for example, from storage, through line 13 connecting with line 14 which diverts the hydrogen fluoride into isomerization reactor feed line 11 in amounts controlled by valve 15. The amount thus charged into the process flow, however, must be limited to that amount only which is necessary to effect the desired isomerization reaction; that is, to an amount not more than that required merely to saturate the hydrocarbon stream without forming a separate hydrogen fluoride phase. A particularly preferred source of the hydrogen fluoride in isomerization reactor 12 is a hydrogen fluoride-containing isobutane stream recovered in a subsequent stage of the process by stripping a C₄ hydrocarbon-hydrogen fluoride-containing fraction from the alkylation reaction product. This stream is generally saturated with hydrogen fluoride

and when mixed with the butene-1-containing olefinic hydrocarbon fraction, supplies a quantity of hydrogen fluoride sufficient to effect the desired isomerization of butene-1 to butene-2. When operating the process on the basis of the latter generally preferred source of hydrogen fluoride the stream of C₄ paraffins saturated with hydrogen fluoride is charged into isomerization reactor feed line 11 from line 16 in amounts controlled by valve 17. Since this stream is generally the most volatile fraction recovered from the alkylate product in the stripping column following the alkylation reactor, the fraction contains a higher proportion of isobutane than the less volatile n-butane which may be present in the alkylate product. The large proportion of isobutane in this fraction desirably increases the ratio of isobutane in the feed to the alkylation reactor when recycled in the system and thus accomplishes a useful purpose in the process.

The mixture of butene-1 and hydrogen-fluoride stream charged into reactor 12 is contacted therein with particles of a suitable solid contacting material, such as copper chips, which promotes mixing of the reactants and enhances the formation of isobutyl fluorides by reaction of butene-1 with the limited quantity of hydrogen fluoride present in the stream. The resulting stream of secondary and tertiary butyl fluorides, butene-2, unconverted butene-1, if any, and other components of the stream formed in reactor 12 pass through hydrofluorination zone 18, and thereafter flow upwardly through a perforated plate suitable for supporting the solid contacting material in a superimposed dehydrofluorination zone 19, containing a solid contact catalyst capable of promoting dehydrofluorination such as calcium fluoride, aluminum fluoride, copper pellets, etc. Dehydrofluorination in zone 19 may be effected at the same or at a higher temperature as that maintained in hydrofluorination zone 18. Thus, zones 18 and 19 may be separately maintained reaction vessels each maintained at different temperatures, or a single combined reactor maintained at an essentially uniform temperature throughout. In the case of a single chamber reaction zone, heating coils may be interposed in column 12 between zones 18 and 19 to heat the fluid stream leaving zone 18 and entering zone 19. At the temperature and pressure conditions maintained in reactor 12, the dehydrofluorination occurring in zone 19 regenerates hydrogen fluoride from the secondary and tertiary butyl fluorides contained in the stream and forms butene-2 as a result of the isomerization occurring through the intermediate isobutyl fluoride formation. The resulting mixture comprising butene-2, unconverted butene-1, if any, and regenerated hydrogen fluoride thereafter progresses into a superimposed hydrofluorination zone wherein an additional quantity of butene-1 is converted to isobutyl fluoride without substantial effect on the butene-2 component of the stream. The isomerization reactor 12, here illustrated as a vertical column containing multiple superimposed hydrofluorinating and dehydrofluorinating zones, may also consist merely of one hydrofluorinating zone followed by one dehydrofluorinating zone; however, the conversion of butene-1 to butene-2 through only one cycle of the reaction is generally incomplete because the amount of hydrogen fluoride present by solubility is less than the stoichiometric amount required for the complete conversion of the olefins present in the stream and it is, therefore, preferred to provide a multistage isomerization reactor wherein the remaining butene-1 may be subjected to a succeeding series of hydrofluorination-dehydrofluorination cycles to convert butene-1 substantially completely to butene-2.

The conversion products formed in isomerization reactor 12 are removed therefrom through line 20 and transferred directly, after cooling in heat exchanger 21, into the alkylation reactor, although in some instances the products may be subjected to a preliminary fractionation, for example, in a depropanizer column, not shown, to

remove propane, propylene and/or propyl fluoride which may be present in the product of the isomerization reaction by virtue of the propylene and propane usually present in the C₄ fractions utilized as feed stock in the process.

The products of the isomerization reaction carried in a stream of isobutane, and comprising butene-2, sec-butyl fluoride, unconverted butene-1, if any, and tert-butyl fluoride, if present, are charged after cooling to the desired alkylation reaction temperature in heat exchanger 21, into alkylation reactor 22. The latter unit is preferably in the form of a stirred pressure autoclave wherein the temperature of the reactants charged thereto may be maintained at from about -30° to about 100° C., preferably from about 0° to about 50° C., and at a pressure sufficient to maintain the reactants and hydrogen fluoride charged thereto in substantially liquid phase, generally at pressures of from atmospheric to about 15 atmospheres. The contents of the reactor are desirably mixed by a suitable form of stirring device such as a series of paddles, orifice mixers or by other means well known in the art.

The proportion of isobutane to butylenes (or their equivalent butyl fluorides) provided in alkylation zone 22 is maintained at molar ratios of from about 5 to 1 to about 15 to 1, the isobutane being made up of fresh isobutane stock charged into the process flow through line 1 and recycle isobutane recovered from the alkylation reaction product stream as an HF-isobutane overhead distilled from the butane stripping column operated in a subsequent stage of the process, as hereinafter described. This fraction comprising predominantly isobutane is charged into reactor 22 through line 23 in an amount controlled by valve 24 or through line 17 into isomerization reactor 12. The total amount of isobutane thus present in alkylation 22 is determined by the amount available from the subsequent isobutane stripper and also the amount available in the C₄ paraffin feed stock charged into the process flow through line 1.

A sufficient quantity of hydrogen fluoride is charged into reactor 22 to catalyze the condensation of isobutane with the butylene or their equivalent butyl fluorides in the stream of isomerization product from reactor 12. Hydrogen fluoride for this purpose is of catalytic concentration, herein specified as "substantially anhydrous" hydrofluoric acid containing not more than about 10% by weight of water, although liquid anhydrous hydrogen fluoride and hydrofluoric acid containing at least 95% hydrogen fluoride is preferred. A major proportion of the hydrogen fluoride required in reactor 22 may be supplied through line 25 as recycled spent alkylation acid recovered from the alkylation reaction products in the settling zone following the alkylation reactor. Desirably, at least a portion of the hydrogen fluoride is fresh make-up acid removed from storage through line 13 which connects with line 14 or from a continuously operated acid regeneration system, the amount charged into alkylation reactor 22 being determined by valve 26 in line 14.

The products of the alkylation reaction which are maintained in liquid phase by the temperature and pressure maintained in zone 22 are removed therefrom through line 27 and valve 28 and charged into receiver vessel 29 wherein a hydrocarbon product phase is separated from a used or "spent" acid phase. These phases separate in vessel 29 into an upper hydrocarbon layer saturated with hydrogen fluoride and a lower spent acid layer which settles to the bottom of vessel 29. The spent acid may be allowed to flow into a settling leg on the receiver vessel such as 30 and withdrawn therefrom through line 31. At least a portion of the spent discharge from the process; the latter withdrawn portion may be subjected to fractional distillation to regenerate substantially anhydrous acid suitable for recycling to the alkylation reactor. Regeneration of the acid by means not shown on the diagram is a well-known procedure in the art and is not directly concerned

with the present invention. A portion of the spent acid may be recycled to the alkylation zone from line 32 through valve 34 by means of pump 35 which discharges the spent acid into line 25 leading into alkylation reactor 22, as aforesaid.

The upper, substantially hydrocarbon layer in receiver vessel 29 is removed therefrom through line 36 with the aid of pump 37 which transfers the HF-saturated hydrocarbon phase into line 38, the latter conduit leading the hydrocarbon into heater 39 wherein the hydrocarbon stream is heated to a temperature sufficient to vaporize a major proportion of the C₄ components from the hydrocarbon alkylate and substantially all of the hydrogen fluoride dissolved in the hydrocarbon alkylate. The hydrocarbon stream at a temperature of from about 10° to about 50° C. is removed from heater 39 through line 40 and valve 41 and charged into isobutane stripping column 42 operated at a temperature and pressure suitable for vaporizing a hydrogen fluoride saturated isobutane stream therefrom. Additional heat for effecting such vaporization may be supplied by a suitable reboiler coil in the lower portion of stripping column 42, such as reboiler 43. The light vapor overhead from column 42 comprising a hydrogen fluoride-isobutane mixture is removed from the column through line 44, liquefied in condenser 45 and the liquefied overhead charged into receiver vessel 46 through line 47 and valve 48. A portion of the hydrogen fluoride component of the vapor overhead may settle out as a dense liquid layer in receiver vessel 46 and may be removed from settling leg 49 through line 6 and pump 6a for recycle to HF saturator column 5 or alkylation reactor 22. The upper hydrocarbon layer saturated with hydrogen fluoride accumulating in receiver 46 is removed therefrom through line 50 by means of pump 51 which discharges the predominantly isobutane stream into line 52. In the preferred method of operating isobutane stripping column 42 at least a portion of the C₄ overhead from the column is returned to the top of column 42 as liquid reflux, the amount of the recycled portion being determined by valve 53 in line 52. The upper layer isobutane fraction accumulating in receiver vessel 46 is saturated with hydrogen fluoride and thus comprises a convenient hydrogen fluoride carrying medium for mixing with the butene-1 containing olefinic feed stock charged into the isomerization stage of the process. The isobutane fraction saturated with hydrogen fluoride may comprise the predominant or sole source of hydrogen fluoride in the isomerization reactor, and in the preferred method of operating the process, said fraction is the sole source of hydrogen fluoride mixed with the olefin fraction subjected to isomerization. In accordance with such preferred method of operation, hydrogen fluoride saturator column 5 may be eliminated from the process flow and the hydrogen fluoride required for isomerization in reactor 12 supplied by the hydrogen fluoride-saturated isobutane recycle stream returned to reactor 12 through line 17. Further, under such modified flow, make-up isobutane (to replace the isobutane converted to alkylate which is removed from the process as product) is introduced with the butene-1 containing olefinic feed or alternatively introduced or a separate stream into alkylation reactor 22.

The high boiling bottoms of the isobutane stripping column 42 contain the desired alkylate product formed in the preceding alkylation reaction, a predominant proportion of which consists of C₈ paraffin hydrocarbons, such as iso-octane (2,2,4-trimethylpentane), the alkylate product being highly desirable for motor fuel use in high compression automotive and aviation engines because of its high performance rating. When operating the process in the manner indicated wherein the butene-1 component of the olefinic hydrocarbon feed stock is isomerized to butene-2 prior to alkylation, the alkylate product has a rich rating performance number (F-4 performance number) of from 145 to 155. The stripper bottoms thus formed are removed from column 42 through

line 54 and valve 55 to storage or to additional fractionation means for separating a more desirable heartcut, as preferred.

The present invention is further illustrated with respect to certain of its specific embodiments in the following example, the specified reaction conditions therein not being intended to limit the broad scope of the invention strictly in accordance thereto.

A synthetic butylene-containing light hydrocarbon fraction was prepared and utilized in the following series of reactions as a source of C₄ olefinic hydrocarbon alkylating agent for condensation with isobutane to form an aviation alkylate. The composition of this fraction in mol percent of its constituents is indicated as follows:

15	Isobutane	0.2
	n-Butane	66.5
	Butene-1	32.0
	Butene-2	1.0
20	Isobutylene	0.0
	C ₅	0.3
	Total	100.0

25 346 grams of the above fraction containing 112 grams of mixed butylenes was mixed with 20 grams of hydrogen fluoride (5.4 weight percent), an amount of hydrogen fluoride which completely dissolved in the hydrocarbons. The mixture was thereafter heated to a temperature of 30 100° C. for 24 minutes. The normally liquid product of the reaction (i. e. boiling at a tempertaure above 40° C.) was 13 grams and contained 2.72% by weight of fluorine. The condensable gases were liquefied, 343 grams being recovered. A fluorine analysis of this product indicated that it contains 2.72% by weight of fluorine and has the following composition, expressed as mol percent of the indicated component:

40	Isobutyl fluoride	15.6
	Isobutane	4.2
	n-Butane	64.2
	Butene-1	13.1
	Butene-2	0.0
45	Isobutylene	0.9
	C ₅	1.8
	C ₆	0.2

50 The condensable gas portion of the effluent of the hydrofluorination reaction and the butyl fluoride formed in the preceding reaction are charged at a temperature of 130° C. over a dehydrofluorination catalyst consisting of pellets of metallic copper at a rate corresponding to 0.8 volume of gas per volume of catalyst per hour. The 55 products of the reaction are separated into a condensable gas fraction and a liquid fraction containing components boiling above 40° C. The condensable gas, containing all of the C₄ components of the product and 2.4% by weight of fluorine is composed of the following constituents in their indicated proportions, expressed as mol percent.

65	Isobutane	4.3
	Isobutyl fluoride	0.0
	n-Butane	64.1
	Butene-1	12.7
	Butene-2	15.6
	Isobutylene	0.7
	C ₅	2.3
70	C ₆	0.3

75 The dehydrofluorination product containing dissolved hydrogen fluoride is thereafter heated under the conditions employed in the initial hydrofluorination reaction and the product separated as indicated above. The organic

11

portion of the condensable gases has the following composition, expressed in mol. percent.

Isobutane	4.2
Isobutyl fluoride	18.6
n-Butane	64.0
Butene-1	5.6
Butene-2	3.2
Isobutylene	0.3
C ₅	3.8
C ₆	0.3

The condensable gas fractions contains approximately 105 grams equivalent of butylene alkylating agent, about 12 mol percent of which is butene-2 and about 67 mol percent of which is isobutyl fluoride, is capable of acting as an alkylating agent similar to butene-2 in the presence of an alkylation catalyst.

The condensable gas fraction is mixed with sufficient isobutane to form a mixture containing an isobutane to butylene (including isobutyl fluoride, isobutylene and butene-1) mole ratio of 15 to 1, 1400 grams of isobutane from an external source being mixed with the above condensable gas fraction for this purpose. The resulting hydrocarbon mixture at a temperature of 43° C. and pressure of 150 lbs./in.² is run into a stirred pressure autoclave of the turbo-mixer type containing about 0.6 volume proportions of the total hydrocarbon feed of anhydrous hydrogen fluoride maintained in liquid phase at a pressure of 150 lbs./in.² forming thereby a mixture containing a hydrocarbon to acid volume ratio in the reactor of about 1.67. The mixture is stirred for a reaction period of about 25 minutes, cooled to about 30° F. and thereafter discharged into a settling vessel to separate a lower spent acid phase from the upper layer hydrocarbon product. The decanted hydrocarbon product after water-washing and treatment with caustic soda to remove acid fluorides is fractionally distilled to separate a debutanized gasoline-boiling range fraction from the alkylate. This fraction has an end boiling point of 338° F. and a rich rating performance number (4.6 cc. per gallon of tetraethyl lead) of 152.

Under the same conditions of alkylation, that is, utilizing a similar ratio of isobutane to butylenes, a similar hydrocarbon to hydrogen fluoride ratio, the same temperature and residence time, the alkylate produced by reacting isobutane with the non-isomerized light hydrocarbon fraction subjected to isomerization in the preceding experiment which contains 32 mole percent butene-1, 1.0 mole percent butene-2 and 0.0 mole percent isobutene yielded a debutanized aviation gasoline stock having a rich rating performance number (plus 4.6 cc. of tetraethyl lead per gallon) of 142.

I claim as my invention:

1. A process for producing an olefin having an intermediate double bond in its carbon atom chain from a hydrocarbon fraction containing a mono-olefin of at least 4 carbon atoms per molecule and having a terminal double bond, which comprises subjecting the hydrocarbon fraction to a hydrofluorination reaction with an amount of hydrogen fluoride not in excess of that which will completely dissolve in said fraction, thereby forming alkyl fluoride in the hydrocarbon fraction, thereafter subjecting said fraction to dehydrofluorination in contact with a dehydrofluorination catalyst to convert said alkyl fluoride

12

to an isomer of said mono-olefin having its double bond more centrally located in the carbon atom chain, thereby liberating free hydrogen fluoride for reaction with additional mono-olefin in the hydrocarbon fraction, and alternately subjecting said fraction to said hydrofluorination and dehydrofluorination reactions until substantially all of said mono-olefin therein has been converted to said isomer.

2. The process of claim 1 further characterized in that said hydrocarbon fraction is a predominantly C₄ fraction and said mono-olefin is butene-1.

3. The process of claim 1 further characterized in that said hydrofluorination and dehydrofluorination reactions are effected in the presence of a diluent comprising an isoparaffin which is subsequently alkylated with said isomer in the presence of hydrogen fluoride from said reactions.

4. The process of claim 3 further characterized in that said hydrocarbon fraction is a predominantly C₄ fraction containing butene-1 as said mono-olefin and said isoparaffin is isobutane which is alkylated with butene-2 produced from the butene-1.

5. The process of claim 1 further characterized in that an isoparaffin is alkylated with said isomer in the presence of hydrogen fluoride catalyst, including the hydrogen fluoride from the hydrofluorination-dehydrofluorination operation, separating from the resultant products an unconverted isoparaffin fraction saturated with hydrogen fluoride and supplying a sufficient amount of the last-named fraction to said operation to furnish the hydrogen fluoride required therein.

6. A process for the alkylation of an isoparaffin which comprises passing a stream of liquid isoparaffinic hydrocarbon through a body of hydrogen fluoride-containing liquid to dissolve hydrogen fluoride in the isoparaffin liquid, separating the HF-isoparaffin solution from said body and adding thereto a mono-olefin of at least 4 carbon atoms per molecule and having a terminal double bond, subjecting the mixture thus formed to alternating hydrofluorination and dehydrofluorination reactions until substantially all of said mono-olefin is converted to an isomer having its double bond more centrally located in the carbon atom chain, supplying the resultant mixture of said isomer, isoparaffin and hydrogen fluoride to an alkylating zone, introducing to said zone sufficient additional hydrogen fluoride to provide therein a catalytic amount of hydrogen fluoride, and reacting said isomer with the isoparaffin in the alkylating zone in the presence of the hydrogen fluoride catalyst.

7. The process of claim 6 further characterized in that said isoparaffin is isobutane and said mono-olefin is butene-1 which is converted to butene-2 by the isomerization.
